UNITED STATES PATENT OFFICE.

THOMAS K. KEITH AND ROSWELL CARLETON, OF HAVERHILL, MASS.

FEED MECHANISM FOR SEWING-MACHINES.

SPECIFICATION forming part of Letters Patent No. 268,804, dated December 12, 1882.

Application filed April 27, 1882. (No model.)

To all whom it may concern:

Be it known that we, THOMAS K. KEITH and ROSWELL CARLETON, both of Haverhill, in the county of Essex and State of Massachusetts, have invented certain Improvements in Feed Mechanism for Sewing-Machines, of which the following is a specification.

This invention has for its object to provide improved feed mechanism for a sewing-machine, whereby any desired series of horizontal movements can be given to the work, so as to cause the stitch-forming mechanism to automatically arrange the stitches in any desired pattern or design.

To these ends our invention consists in the employment of pattern-cams, rotated, step by step, by the power of the machine, and a work holding and feeding device capable of a horizontal movement in any direction on the bed of the machine, and operated by said pattern-cams to give the work the desired series of movements.

The invention also consists in the provision of means for automatically raising the presser-foot while the work is being fed, and allowing it to hold the work when the stitches are being formed.

The invention also consists in certain details of construction, all of which we will now proceed to describe and claim.

Of the accompanying drawings, forming a part of this specification, Figure 1 represents a side elevation of a machine embodying our invention. Fig. 2 represents a top view of the same with a portion of the arm broken away. Fig. 3 represents an end view of the arm of the machine with the face-plate removed. Fig. 4 represents a section on line xx , Fig. 1. Fig. 5 represents a design formed in stitches by the machine.

The same letters of reference indicate the same parts in all the figures.

In the drawings, A represents the bed of a sewing-machine. B represents the arm; C, the needle; D, the presser-foot, and E' the shuttle, said parts operating in the usual manner.

In the bed A are transverse dovetail grooves E E, extending from front to back, and in these grooves are fitted slides F F, which are adapted to reciprocate in said grooves. The slides F F are connected at their ends by plates G G,

which constitute guides at right angles to the grooves E.

I represents a plate fitted to and adapted to slide between the guides G G, and provided with a hinged plate, J, adapted to clamp the work against the plate I. The plates I and J are provided with large coinciding orifices, which are under the presser-foot and needle, so that the plates do not obstruct the operation of the stitch-forming mechanism.

K represents a stud journaled in the rear portion of the arm of the machine, and provided with a ratchet, L, which is rotated, step by step, by a pawl, M, operated by a rod, N, bell-crank lever O, and arm P, and an eccentric, Q, on the driving-shaft R of the machine. On the stud K is placed a pair of pattern cams or plates, S T, which are connected by a pin, U, with the ratchet L, so as to rotate therewith. The plate S has a cam-groove, a, and the plate T a cam-groove, b.

c d represent levers pivoted to a stud, e, on the arm of the machine. The lever c is provided with a pin or roller, c', which enters the cam-groove a, and the lever d is provided with a pin, d', which enters the cam-groove b. The levers are thus caused to be oscillated by the rotary movements of the plates T S. The lower end of the lever c is connected with a bell-crank lever, h, which is pivoted at i to the bed of the machine, and is connected by a link, j, with one of the guides G. The lever d is connected by a rod, d', with the plate I.

It will be seen from the foregoing that the oscillations of the lever c will impart through the lever h and link j a reciprocating movement to the slides F F, guides G G, and plate I, carrying said parts toward and from the front of the machine. At the same time the oscillations of the lever d impart through the rod d' a reciprocating movement to the plate I in a direction at right angles to the line of movement imparted to the slides F and guides G. It is obvious, therefore, that the plate I is capable of moving horizontally in any direction, and that by the combined action of the cam-grooves a b a series of movements are imparted to the plate I, and the work held thereon, whereby the stitches formed are combined automatically in a design which is governed by the form of the cam-grooves. The grooves shown in the draw-

ings are adapted to move the work so as to form the leaf-shaped design shown in Fig. 5; but it is obvious that a different design can be produced by differently-shaped cams, so that by 5 providing a number of pairs or sets of cams, each differing from the others, a corresponding number of different designs may be produced.

The plates S T are adapted to be readily applied to and removed from the stud K. We 10 prefer to secure the plates to the stud by means of a spring-hook, m, placed in a slot in the stud, and having a beveled outer end, which yields when the plates are moved onto the stud, and springs out and prevents the withdrawal of the 15 plates when they are in place.

The presser-bar D' is provided with a pivoted lever, n, the lower end of which bears on the lower end of the casing on the end of the arm B, and its other end projects upwardly toward 20 the needle-bar C'. The needle-bar has a pin, p, which, when said bar rises, strikes the lever n and turns it on its pivot so as to cause it to raise the presser-bar. The foot is thus raised slightly with the needle, so that it will not impede the movements of the work. When the 25 needle-bar descends the pin p releases the lever n and the presser-bar drops.

We claim—

1. In combination with the stitch-forming

mechanism of a sewing-machine, a work-holding plate, means, substantially as described, whereby said plate is enabled to move horizontally in any direction on the bed of the machine, pattern-cams rotated by the power of the machine, and intermediate devices whereby said 35 cams are caused to operate the work-holding plate, as set forth.

2. The combination of the bed having guide-grooves E, slides F, adapted to move in said grooves, and supporting-guides G, a work-holding plate, I, adapted to slide in the guides G, the pattern-cams ab, and intermediate connecting devices, all arranged and operated as set forth.

3. The combination of the arm B, the presser-bar having the pivoted lever n, and the needle-bar having the pin, whereby the presser-foot is raised with the needle, as set forth.

In testimony whereof we have signed our names to this specification, in the presence of two subscribing witnesses, this 21st day of April, 1882.

THOMAS K. KEITH.
ROSWELL CARLETON.
